UNITED STATES PATENT OFFICE.

HENRI RAYMOND GUYOT, OF PARIS, FRANCE.

COOLER ADAPTED FOR USE AS A RADIATOR OR CONDENSER.

1,256,998.

Specification of Letters Patent. Patented Feb. 19, 1918.

Application filed April 27, 1916. Serial No. 93,824.

To all whom it may concern:

Be it known that I, HENRI RAYMOND GUYOT, of 54 Avenue Jean Jaurès, Paris, in the Republic of France, engineer, have invented a Cooler Adapted for Use as a Radiator or Condenser, of which the following is a full, clear, and exact description.

This invention relates to a cooler adapted to be used as a radiator or condenser and 10 designed so as to offer large radiating surfaces for the purpose of efficiently employing the cooling air or fluid passing therethrough.

The cooler is constituted essentially by:

(a) A set of radiation surfaces or gills (extending for instance in a horizontal direction) separated from one another by a plurality of vertically-extending combs or distance pieces adapted to engage the ends 20 of the gills and separated from one another to an extent approximately equal to the distance between the gills so as to form cells which give to the assemblage the aspect of a honeycomb;

(b) A second set of horizontally-extending radiating gills of a length less than that of the gills of the first set above referred to and arranged so that their edges are located in the central position of the 30 cells formed by the first set of radiating gills and the comb-like distance pieces;

(c) A plurality of tubes passing through the two sets of gills and serving as conduits for the fluid to be cooled.

By means of this construction each cell terminates in a double passage and the air (for instance) which comes up against the edge of the small intermediate gill produces eddies which reduce the speed at which the 40 air is passed through the apparatus. Furthermore, the friction between this air and the intermediate gills has also for effect to set up a resistance which reduces the speed of passage of the air, and the intermediate 45 gills themselves have for effect to increase the radiating area.

In this construction the assemblage of radiating gills, distance pieces and tubes, forms a rigid structure as the distance pieces 50 form struts between the main radiating gills.

It is to be noted that the passages for the tubes through the gills are formed by pressing out the metal so that these passages are 55 surrounded by a metallic collar engaging the tubes from which it results that the

maximum of radiating surface and efficient employment of the cooling fluid are obtained.

The invention is illustrated by way of example in the annexed drawing wherein Figure 1 is a front elevation of part of a cooler wherein the tubes through which passes the fluid to be cooled extend in a direction parallel with that of the distance pieces and hence are normal to the gills.

Fig. 2 is a vertical section on line 2-2 of Fig. 3, while Fig. 3 is a similar view on line 3-3 of Fig. 2.

Fig. 4 illustrates a portion of one of the 70 comb-like distance pieces.

Fig. 5 is a vertical section showing a number of gills.

Figs. 6 and 7 are plan views of the large 75 and of the small gills respectively.

Figs. 8, 9 and 10 are horizontal sections of modified forms of tube for use in the cooler.

Fig. 11 is a front elevation of one of the tubes shown in Fig. 10.

Fig. 12 is a horizontal section of another form of tube which may be used in the cooler.

Fig. 13 is a vertical section on line 13-13 of Fig. 14, of a modified form of construction of cooler wherein the tubes for the passage of the fluid to be cooled extend in a direction normal to that of the distance pieces and of the gills.

Fig. 14 is a section on line 14-14 of Fig. 13.

Fig. 15 is a horizontal section of another form of tube adapted for use in the construction of cooler shown in Figs. 13 and 14.

As will be seen in Figs. 1 to 7 of the drawings, this construction of cooler comprises a first set of radiating gills *a* (extending for instance in a horizontal direction) held together by vertically-extending comb-like pieces *b* which engage the ends of the gills *a* and are spaced apart to an extent approximately equal to the distance between the gills, so as to form cells which give to the assemblage the aspect of a honeycomb.

Between the gills of the first set are mounted a second set of radiating gills *c* of a length smaller than that of the gills of the first set and arranged so as to present their edge in the middle of the cells formed by the gills appertaining to the first set and the distance pieces.

The two sets of gills are perforated by

pressing out the metal to form around each of the perforations a collar *d*, the perforations being staggered and adapted for the reception of the cylindrical tubes *e* 5 through which passes the fluid to be cooled.

Instead of using cylindrical tubes as above described, use may be made of flattened tubes *e'* as shown in Fig. 8, or of cylindrical tubes *e''* connected together in group as 10 shown in Fig. 9.

Use may also be made of tubes *e'''* constituted by two corrugated sheets laid the one on the other as shown in Figs. 10 and 11. One of the sheets is furnished with ribs *f* 15 crossing one another and constituting a number of small channels. The two sheets, instead of being assembled together as above set forth to form a conduit, may be arranged in the reverse direction so as to form 20 tubular conduits *e''* (Fig. 12).

In the modified form of cooler illustrated in Figs. 13 and 14, use is made of flattened tubes *e'''* formed with an extension as at *e''* the extension being slotted so as to engage 25 in the distance pieces *b*, said tubes extending in a direction normal to the pieces *b*. In this modification use may also be made of multiple tubes *e''''* assembled together as shown in Fig. 15.

30 Claims:

1. A cooling device comprising the combination of tubes for the passage of the fluid to be cooled, a set of large radiation elements on said tubes, a set of small radiation 35 elements on said tubes, said large and small radiation elements being arranged in alternation on said tubes.

2. A cooling device comprising the combination of tubes for the passage of the fluid 40 to be cooled, a set of large radiation gills on said tubes, a set of small radiation gills on said tubes, said large and small radiation gills being arranged in alternation on said tubes and being apertured for the passage 45 therethrough of said tubes.

3. A cooling device comprising the combination of tubes for the passage of the fluid to be cooled, a set of large radiation gills on said tubes, a set of small radiation gills 50 on said tubes, said large and small gills being arranged in alternation on said tubes and being apertured for the passage therethrough of said tubes, and distance pieces between the individual members of said set 55 of large radiation gills.

4. A cooling device comprising the combination of tubes for the passage of the fluid to be cooled, a set of large radiation gills on 60 said tubes, a set of small radiation gills on said tubes, said large and small gills being arranged in alternation on said tubes and being apertured for the passage therethrough of said tubes, distance pieces between the individual members of said set 65 of large radiation gills, said large radiation

gills being slotted and said distance pieces being constituted by notched plates engaging said large radiation gills.

5. A cooling device comprising the combination of tubes for the passage of the fluid to be cooled, a set of large radiation gills on said tubes, a set of small radiation gills on said tubes, said large and small gills being arranged in alternation on said tubes and being apertured for the passage therethrough of said tubes, distance pieces between the individual members of said set of large radiation gills, said large and small radiation gills having collars at the edges of the apertures, said collars engaging said tubes.

6. A cooling device comprising the combination of tubes for the passage of the fluid to be cooled, a set of large radiation gills on said tubes, a set of small radiation gills on said tubes, said large and small gills being arranged in alternation on said tubes and being apertured for the passage therethrough of said tubes, distance pieces between the individual members of said set of large radiation gills, said large radiation gills being slotted and said distance pieces being constituted by notched plates engaging said large radiation gills, said large and small radiation gills having collars at the edges of the apertures, said collars engaging said tubes.

7. A cooling device comprising the combination of tubes for the passage of the fluid to be cooled, said tubes being arranged in 100 rows, connecting pieces between the adjacent tubes of each row, a set of large radiation gills on said tubes, a set of small radiation gills on said tubes, said large and small gills being arranged in alternation on said tubes 105 and being apertured for the passage therethrough of said tubes, and distance pieces between the individual members of said set of large radiation gills.

8. A cooling device comprising the combination of tubes for the passage of the fluid to be cooled, said tubes being arranged in rows, connecting pieces between the adjacent tubes of each row, a set of large radiation gills on said tubes, a set of small radiation 115 gills on said tubes, said large and small gills being arranged in alternation on said tubes and being apertured for the passage therethrough of said tubes, and distance pieces between the individual members of said set of 120 large radiation gills, said large radiation gills being slotted and said distance pieces being constituted by notched plates engaging said large radiation gills.

9. A cooling device comprising the combination of tubes for the passage of the fluid to be cooled, said tubes being arranged in rows, connecting pieces between the adjacent tubes of each row, a set of large radiation gills on said tubes, a set of small radiation 125 gills on said tubes, said large and small gills being arranged in alternation on said tubes and being apertured for the passage therethrough of said tubes, and distance pieces between the individual members of said set of 130 large radiation gills.

gills on said tubes, said large and small gills being arranged in alternation on said tubes and being apertured for the passage therethrough of said tubes, and distance pieces between the individual members of 5 said set of large radiation gills, said large and small radiation gills having collars at the edges of the apertures, said collars engaging said tubes.

10. 10. A cooling device comprising the combination of tubes for the passage of the fluid to be cooled, said tubes being arranged in rows, connecting pieces between the adjacent tubes of each row, a set of large radiation gills on said tubes, a set of small radiation gills on said tubes, said large and small gills being arranged in alternation on said tubes and being apertured for the passage therethrough of said tubes, and distance 15 pieces between the individual members of 20 said set of large radiation gills, said large radiation gills being slotted and said distance pieces being constituted by notched plates engaging said large radiation gills, 25 said large and small radiation gills having collars at the edges of the apertures, said collars engaging said tubes.

11. A cooling device comprising the combination of tubes for the passage of the fluid 30 to be cooled, said tubes being arranged in rows, connecting pieces between the adjacent tubes of each row, the tubes and connecting

pieces of each row being constituted by a pair of juxtaposed half tubes and connecting pieces, a set of large radiation gills on said tubes, a set of small radiation gills on said tubes, said large and small gills being arranged in alternation on said tubes and being apertured for the passage therethrough of said tubes, and distance pieces between 35 40 the individual members of said set of large radiation gills.

12. A cooling device comprising the combination of tubes for the passage of the fluid to be cooled, said tubes being arranged in rows, connecting pieces between the adjacent tubes of each row, the tubes and connecting pieces of each row being constituted by a pair of juxtaposed half tubes and connecting pieces, ribs on said tubes, a set of large radiation gills on said tubes, a set of small radiation gills on said tubes, said large and small gills being arranged in alternation on 45 50 said tubes and being apertured for the passage therethrough of said tubes, and distance pieces between the individual members of 55 said set of large radiation gills.

The foregoing specification of my "cooler" adapted for use as a radiator or condenser", signed by me this fifth day of April, 1916. 60

HENRI RAYMOND GUYOT.
